UNITED STATES PATENT OFFICE.

WILLIAM A. BRACKEN, OF ELDORADO, KANSAS.

AUTOMOBILE AWNING.

Application filed April 13, 1928. Serial No. 269,690.

This invention relates to rolling awning structures of the spring controlled type for use in connection with doors, windows, etc., but more particularly to a means for latching the shifting yoke of the awning body in adjusted position to maintain the latter extended with respect to its winding roller, and the invention has for its object to provide, in a manner as hereinafter set forth, 10 a new, improved, compact, durable, expeditiously operated and thoroughly efficient latching means for the purpose referred to.

With the foregoing and other objects in view the invention consists of the novel construction, combination and arrangement of parts as hereinafter more specifically described, and illustrated in the accompanying drawings, wherein is shown an embodiment of the invention, but it is to be understood 20 that changes, variations and modifications can be resorted to which fall within the scope of the claims hereunto appended.

In the drawings wherein like reference characters denote corresponding parts 25 throughout the several views:

Figure 1 is a vertical sectional view of an awning structure when extended and arranged with respect to a window and further illustrating a latching means for the adjusting yoke for the awning body in accordance with this invention and in position for latching the awning body extended with respect to its winding roller.

Figure 2 is a fragmentary view in sectional elevation illustrating a spring controlled rolling awning structure and a latching means in accordance with this invention in adaptation therewith.

Figure 3 is a section on line 3—3 of Figure 2.

The drawing illustrates but one arm of the shifting yoke for the awning body and a latching means associated with such arm, but it is to be understood that a latching 45 means is associated with each arm of the awning body shifting yoke.

Referring to the drawings in detail 1 denotes a side rail of a window frame or door opening, 2 the top rail, 3 a vertically adjustable transparent panel or glass and the foregoing elements are of known construction.

Secured to the inner face of the side rail 1 is a supporting bracket 4 provided at its top with a rearward extension 5 to receive 55 one of the pintles of the spring controlled

winding roller 6 for the awning body 7. Holdfast devices 8 are provided for securing the bracket 4 to the rail 1. The bracket 4 is slotted as at 9, 10 for the passage of the holdfast devices and said slots permit of the 60 bracket 4 being vertically adjusted relative to the rail 1. The outer face of the bracket 4, at the lower end thereof has formed integral therewith a circular boss 11 provided on its edge with a set of ratchet teeth 12. 65 The inner face of the bracket 4 at its lower end is formed with a concavity 13 and the bracket 4 at its lower end is furthermore formed with an opening 14 which communicates with the concavity 13. 70

A shifting yoke for the awning body 7 is indicated at 15 and one of the arms of the latter at 16. The outer or free end of the arm 16 is beveled as at 17 and in proximity to said beveled end the arm 16 is provided 75 with an opening 18 through which a stop is extended and by way of example the stop is illustrated as a cotter pin and indicated at 19.

Opposing the boss 11, and of a diameter 80 slightly greater than the diameter thereof, is a circular disc 20 and interposed between the latter and the boss 11 is a washer 21. The disc 20 is formed with a centrally disposed opening 22. Extending through the 85 opening 22, washer 21 and opening 14 and into the concavity 13 is a pivot member 23 having its outer end provided with a head 24 which abuts against the outer face of the disc 20. The pivot member 23 carries 90 a washer 26 and has extending through that end thereof positioned within the concavity 13 a cotter pin 27 which coacts with the head 24 for connecting the member 23 to the bracket 4. 95

Formed integral with and extending from the disc 20 is a tubular member 28 which constitutes a guide for the arm 16. The member 28 is cut away, as at 29 to provide a clearance for the stop 19 and also to form 100 a shoulder 30 which is engaged by the stop 19 to arrest the outward movement of the arm 16 relative to the guide 28. The stop 19 slidably connects the arm 16 to the tubular guide 28. 105

The controlling spring of the winding roller 6 normally tends to maintain the stop 19 against the shoulder 30. The end 17 of the arm 16 coacts with the teeth 12 for the purpose of latching the yoke 15 in an ad- 110

justed position whereby the awning body 7 will be held extended with respect to the winding roller 6.

The yoke can be swung on the pivot member 23 and after it has been shifted to the desired position, it is latched in such position by the engagement of the free end 17 of the arm 16 with the ratchet teeth 12 of the bosses 11. The clearance 29 permits of a sufficient movement of the arm 16 relative to the boss 11 so that the end 17 can clear the teeth 12 for the purpose of releasing the yoke and when the yoke is released it will be drawn upwardly, due to the action of the controlling spring for the winding roller causing the awning body 7 to wind on said roller 6.

It is thought the many advantages of a latching means, in accordance with this invention and for the purpose set forth, can be readily understood, and although the preferred embodiment of the invention is as illustrated and described, yet it is to be understood that changes in the details of construction can be had which fall within the scope of the invention as claimed.

What I claim is:

1. In a rolling awning structure of that type including a spring controlled awning body adjusting yoke, the combination with one of the arms of the yoke, of a tubular guide having said arm slidably extending therethrough, said guide being cut away internally at its inner end to provide a shoulder and a clearance, means carried by said arm adjacent the free end thereof, operating in said clearance and adapted to abut said shoulder to arrest outward shift of the arm with respect to said guide, a support provided with teeth opposing the inner end of said sleeve and coacting with the free end of said arm for latching the yoke, a disc opposing the toothed portion of the support, connected to the guide and offset with respect to said arm, and coupling means between the disc and the toothed portion of the support and providing a pivot for the disc.

2. A combined attaching, latching and pivoting means for an arm of a spring controlled awning body adjusting yoke comprising a tubular guide adapted to have said arm slidably extend therethrough and having within its inner end a clearance and a shoulder, said shoulder arranged forwardly of the clearance, means arranged in said clearance, carried by said arm and coacting with said shoulder for limiting the outward shift of the arm, a support provided with an offset portion having a toothed edge opposing the inner end of said guide and engageable by the free end of said arm for latching the yoke, a disc connected to the inner end of the sleeve, offset with respect to said arm and opposing said offset portion, and means connected to the support and to

the disc for coupling them together and providing a pivot for the disc.

3. A combined attaching, latching and pivoting means for an arm of a spring controlled awning body adjusting yoke comprising a tubular guide adapted to have said arm slidably extend therethrough and having within its inner end a clearance and a shoulder, said shoulder arranged forwardly of the clearance, means arranged in said clearance, carried by said arm and coacting with said shoulder for limiting the outward shift of the arm, a support provided with an offset portion having a toothed edge opposing the inner end of said guide and engageable by the free end of said arm for latching the yoke, a disc connected to the inner end of the sleeve, offset with respect to said arm and opposing said offset portion, a headed member extending through the disc and into said support at the offset portion thereof and providing a pivot for the disc, the head of said member positioned against the outer face of the disc, and means arranged within the support for connecting said member thereto.

4. A combined attaching, latching and pivoting means for an arm of a spring controlled awning body adjusting yoke comprising a tubular guide adapted to have said arm slidably extend therethrough and having within its inner end a clearance and a shoulder, said shoulder arranged forwardly of the clearance, means arranged in said clearance, carried by said arm and coacting with said shoulder for limiting the outward shift of the arm, a support provided with an offset portion having a toothed edge opposing the inner end of said guide and engageable by the free end of said arm for latching the yoke, a disc connected to the inner end of the sleeve, offset with respect to said arm and opposing said offset portion, a headed member extending through the disc and into said support at the offset portion thereof and providing a pivot for the disc, the head of said member positioned against the outer face of the disc, means arranged within the support for connecting said member thereto, and a washer member interposed between said disc and offset portion of the support.

5. In a spring controlled rolling awning structure, the combination of an arm of the awning body shifting yoke, a stop carried by said arm in proximity to its free end, a tubular guide mounted on the arm and provided within its inner end with a clearance for the stop and further having an internal shoulder at the forward end of the clearance to arrest the outward shifting of the arm relative to the guide, a disc extended from said guide, a support provided with ratchet teeth coacting with the free end of said arm to latch the yoke in adjusted posi-

tion, and means connected with said support and to said disc for pivotally supporting the latter and for coupling it to the support.

6. In a spring controlled rolling awning structure, the combination of a bracket provided with a boss having its edges toothed, a disc opposing the boss, means attached to the bracket, extended from the boss and providing a combined pivot and coupling means for the disc, a pin adapted to be connected to one of the arms of the yoke in proximity to the free end of said arm, a tubular guide

member adapted to be mounted on said arm, carried by the disc and extended over the edge of the boss whereby said arm will oppose the boss, said guide provided therein with means coacting with said stop to arrest the outward shifting of such arm relative to the guide, and said teeth coacting with said arm for latching the yoke in adjusted position. 15 20

In testimony whereof, I affix my signature hereto.

WILLIAM A. BRACKEN.
